UNITED STATES PATENT OFFICE

WILLIAM EUGENE BUCHANAN, OF APPLETON, WISCONSIN, ASSIGNOR TO APPLETON WIRE WORKS, INC., OF APPLETON, WISCONSIN, A CORPORATION OF WISCONSIN

LOOM APPARATUS

Application filed June 4, 1931. Serial No. 542,076.

The invention relates to wire-weaving looms.

In my co-pending application for Letters Patent for method and means for weaving 5 Fourdrinier wires, Serial No. 463,171, filed June 23, 1930, there was disclosed loom apparatus including a straight-edged cloth-engaging member extending transversely above the wire cloth adjacent the fell for securing 10 the production of strong and durable wire cloth with a smooth flat surface.

It is an object of the present invention to effect improvements in this apparatus to the end of facilitating the positioning of the 15 cloth-engaging member with respect to the cloth and increasing the smoothness and durability of the cloth-engaging member.

A more specific object of the invention is to form the cloth-engaging member by a 20 shiftably mounted metal bar coated with chromium or other hard wear-resisting metal and presenting a plurality of selectively usable polished wearing surfaces.

The invention further consists in the several features hereinafter set forth and more particularly defined by the annexed claims.

In the accompanying drawing

Fig. 1 is a detail sectional elevation of a portion of a wire-weaving loom embodying 30 the invention;

Fig. 2 is a fragmentary top plan view thereof, and

Fig. 3 is a detail sectional elevation of the cloth-engaging member.

In the drawing, the numeral 10 indicates 35 the frame of a wire-weaving loom on the upper portions of which is suspended a swinging lay 11 provided with the usual reed 12. The side members of the frame 10 are connected at their forward portions by the usual breast beam 13 over which the finished wire cloth 14 passes on its way to the cloth beam (not shown). Warp wires 15 extend from 40 a warp beam (not shown) and pass between the dents of the reed, as usual, to the finished wire cloth 14 of which they become a part. In Fig. 1, the lay is shown in full lines at 45 its forward position engaging the face of the work, and the retracted position of the lay is indicated by dotted lines. The general

construction of the loom is exemplified in United States Patent No. 1,391,435, issued September 20, 1921, to Albert B. Weissenborn. In a loom of the general type shown in this patent, the swinging lay operates as usual to beat up the weft wire left by the shuttle in its travel through the shed formed between the warp wires by the alternate reciprocation of the heddles. At the moment the reed strikes the newly laid weft wire, 55 a lateral component of force is present displacing the newly woven cloth upwardly and causing it to vibrate. Under normal weaving conditions, the wire cloth remains flat because the gage, temper and spacing of the warp and weft wires are suitably selected. However, when any departure is made from 60 specifications known to be favorable to the production of flat cloth, it is found that ridges or waves appear in the newly woven cloth, caused in some measure by unequal displacement of the warp wires from the 65 plane of the cloth.

In order to overcome this difficulty and to permit the weaving of flat wire cloth of 70 widely varying specifications, means are provided engaging the upper surface of the wire cloth adjacent the fell to prevent any vibration of the newly woven cloth and to hold the cloth perfectly flat at the moment 75 the reed strikes the fell.

Brackets 16 are mounted at the opposite ends of the breast beam 13 and support thereon a channel beam 17 extending above and in spaced parallel relation to the breast beam. 80 In the case of the wide loom, the channel beam 17 may be supported at intermediate portions by one or more standards 18. Brackets 19 are secured to the channel 17 and are provided with arms 20 extending toward the fell. Brackets 21 are clamped to the arms 20 and are provided with inclined flanged portions to which is fixedly secured 85 a flat inclined metal bar 22 extending across and above the newly woven cloth in parallel 90 adjacent relation to the fell and spaced above the cloth, the inclination of the bar permitting the weaver to view the newly formed edge of the cloth.

A flat metal bar 23 having a polished coat- 100

ing 24 of chromium or other hard wear-resisting metal extends along the lower portion of the bar 22 and is provided with a series of medially disposed spaced transverse openings 25 through which pass screws 26 threaded into the bar 22 to clamp the bar 23 in place, the openings being larger than the screw shanks to permit adjustment of the bar. In the case of chromium, the metal may be electroplated onto the bar 23. The bar 23 is provided with rounded opposite edges 27, the lower of which bears against the upper surface of the wire cloth near the fell. The bar bears down on the cloth with sufficient pressure to insure the engagement of the cloth therewith at all points, but ordinarily this pressure need not be very heavy. The proper contact of the bar with the cloth can readily be obtained by shifting the bar in its plane. This displacement of the cloth by the bar is quite small and insufficient to affect the tension in the warp banks of the shed.

In operation, when the lay falls, bringing the reed forcibly against the newly laid weft wire, the upward component of force on the edge of the cloth is communicated to, and resisted by, the stationary bars 23 and 22 which prevent vibration or displacement of the cloth. The bars maintain the newly formed edge of the wire cloth perfectly flat and function much the same as an anvil in resisting the upward force on the cloth.

By reason of the hard polished wear-resisting surface on the bar 23 the cloth will not be marked or scored, and when the contacting edge eventually becomes worn, three other fresh edges are available for selective use by reversing the bar side for side and end for end. All adjustments of the cloth-engaging bar 23 can be effected without disturbing the position of the much heavier and rigidly mounted supporting bar 22.

What I claim as new and desire to secure by Letters Patent is:

1. In a loom, the combination of a frame for supporting thereon warp wires and woven wire cloth, a lay swingably mounted on the frame for beating up weft wires into the fell, a support extending transversely of the wire cloth, cloth-leveling bar shiftably mounted on said support and extending transversely of the cloth and having a hard polished surface engaging the cloth adjacent the fell, and means for securing said shiftably mounted bar to said support in a selected position with respect to the cloth.

2. In a loom, the combination of a frame for supporting thereon warp wires and woven wire cloth, a lay swingably mounted on the frame for beating up weft wires into the fell, a support extending transversely of the cloth, a flat shiftably mounted cloth-leveling bar on said support extending transversely of the cloth and having straight opposite edges selectively engaging the cloth adjacent the fell,

and means for securing said bar to said support.

3. A cloth-leveling member for a wire-weaving loom comprising a bar engageable with the surface of the wire cloth adjacent the fell to level the cloth during the lay blow and having a plurality of selectively usable polished chromium-plated wearing surfaces. 70

4. A cloth-leveling member for a wire-weaving loom comprising a flat bar engageable with the surface of the wire cloth adjacent the fell to level the cloth during the lay blow and having selectively usable polished chromium-plated wearing surfaces at opposite edges. 75

5. A cloth-leveling member for wire-weaving looms comprising a bar engageable with the surface of the wire cloth adjacent the fell to level the cloth during the lay blow and having a cloth-engaging coating of hard polished wear-resisting metal. 80

6. In a loom, the combination of a frame for supporting thereon warp wires and woven wire cloth, and a bar extending transversely of the cloth in engagement therewith and having a coating of hard wear-resisting metal presenting a plurality of selectively usable polished cloth-engaging surfaces. 90

In testimony whereof, I affix my signature. WILLIAM EUGENE BUCHANAN. 95
